UNITED STATES PATENT OFFICE.

CHARLES JOSEPH KIRCH, OF KEOKUK, IOWA.

SLOP JAR OR PAIL.

No. 890,517.

Specification of Letters Patent.

Patented June 9, 1908.

Application filed April 21, 1906. Serial No. 313,043.

To all whom it may concern:

Be it known that I, CHARLES JOSEPH KIRCH, a citizen of the United States, residing at Keokuk, in the county of Lee and 5 State of Iowa, have invented new and useful Improvements in Slop Jars or Pails, of which the following is a specification.

This invention relates to slop jars or pails, the object of the invention being to provide 10 an article of the class referred to which will effectively prevent noxious odors from escaping from the slop jar after the cover or lid is placed thereon, the joint between the cover and the slop jar or pail proper embodying a 15 liquid seal.

A further object of the invention is to provide a slop jar or pail of such construction that the contents thereof may be poured out 20 without interfering with the liquid seal and so that any surplus water which is not poured off the rim of the pail will be drained back into the main body of the slop jar or pail.

With the above and other objects in view, the invention consists in the novel construction, 25 combination and arrangement of parts, hereinafter more fully described, illustrated and claimed.

In the accompanying drawings, Figure 1 is a vertical diametrical section through a slop 30 jar embodying the present invention. Fig. 2 is a plan view of the same with the cover removed.

Referring to the drawings, 1 designates a jar, pail or bucket of any suitable size or 35 shape, the same being, for the purpose of carrying out this invention, provided with an annular supporting ledge 2 a short distance below the top or rim thereof, the extreme top edge of the pail being rolled outward to form 40 a reinforcing rim or bead 3 which forms a support for the cover.

The cover 4 is of dished form, as shown in Fig. 1, and is provided with a marginal circumferential flange 5 which rests upon the 45 rim 3 and further provided with a depending flange 6 which extends downward inside of the rim 3 into the water space hereinafter described.

Supported on the ledge 2 is a frusto-conical rim 7, the lower edge of which is preferably soldered or otherwise secured to the in-

side of the pail by a liquid-tight joint. The rim 7 inclines upwardly and inwardly away from the oppositely lying portion of the pail or jar to leave a V-shaped annular liquid-containing space 8 into which the flange 6 of the cover fits, said flange being partially submerged in the liquid so as to form an absolutely tight joint or seal between the jar or pail and the cover thereof, which has the effect of preventing noxious odors from escaping from the jar.

The conical rim 7 extends above the plane of the top of the pail or jar, as clearly shown in Fig. 1, and the upper edge thereof is provided with an inwardly extending seat flange 9 which leaves a substantially elliptical opening, the flange 9 forming a commode seat which is located above the plane of the rim at the top of the jar or pail. This rim is cut 70 away at one side to form a pouring opening, the lower edge 10 of said opening determining the level of water contained in the space 8 and being located below the plane of the top of the rim 3, whereby the water will be 75 drained from the space 8 back into the pail or bucket and yet leave sufficient water in said space to form a liquid seal in which the bottom portion of the flange 6 of the cover is received.

The jar, pail or bucket may be manufactured of sheet metal, enamel ware, porcelain, fiber or earthen ware and may be made of any suitable size. If desired, the cover may be provided with a rubber rim or gasket 85 where it fits upon the jar or pail.

The same principle hereinbefore described may be applied to water coolers and the like for the purpose of excluding air and thereby effecting a material saving in ice.

I claim:

A device of the character described comprising a slop jar with a surrounding reinforcing bead on its upper edge, a surrounding ledge below the bead, a frusto-conical rim 95 having its lower edge secured to the ledge, said ledge being inclined upwardly and inwardly and away from the top of the pail to provide a V-shaped space therebetween, a cover having an angular flange having one 100 portion mounted on the bead and the other portion extending downwardly and against

the upper portion of the jar, said conical rim extending above the bead to provide a com-
mode seat, and said rim having an incut
which serves as a pouring opening the lower
5 edge of which serves to determine the level
of water contained in said V-shaped space,
substantially as specified.

In testimony whereof, I affix my signature
in presence of two witnesses.

CHARLES JOSEPH KIRCH.
